W. E. RUPE

MACHINE FOR CUTTING METALLIC RIMS OR FELLIES

Filed Feb. 13, 1922

UNITED STATES PATENT OFFICE.

WILLARD E. RUPE, OF STURGIS, MICHIGAN.

MACHINE FOR CUTTING METALLIC RIMS OR FELLIES.

Application filed February 13, 1922. Serial No. 536,311.

To all whom it may concern:

Be it known that I, WILLARD E. RUPE, a citizen of the United States, residing at Sturgis, county of St. Joseph, State of Michigan, have invented certain new and useful Improvements in Machines for Cutting Metallic Rims or Fellies, of which the following is a specification.

This invention relates to improvements in machines for cutting metallic rims or fellies to length.

The objects of the invention are:

First, to provide improved means of cutting metallic fellies from a coiled strip to have them of precisely identical lengths.

Second, to provide such a machine which will effectively cut previously coiled channel-shaped fellies.

Third, to provide improved clamping means for effectively supporting a felly while it is being cut.

Further objects and objects relating to details and economies of construction and operation will definitely appear from the detailed description to follow. I accomplish the objects of the invention by the devices and means described in the following specification. The invention is clearly defined and pointed out in the claims.

A structure which is a preferred embodiment of my invention is illustrated in the accompanying drawing, forming a part of this specification, in which:

Fig. I is a perspective view of a punch and press embodying my improved felly holding and cutting devices.

Fig. II is a detail elevation view from the front of the machine seen in Fig. I, the coil supporting pipe being omitted. The latch lever and segment are also omitted.

Fig. III is an enlarged detail elevation view of the punch part and a portion of the coil supporting part of my improved machine with the punch raised, adjacent coils of the felly material being shown in section.

In the drawing similar numerals of reference refer to similar parts throughout the several views.

Considering the numbered parts of the drawing by the numbers, 1 is the frame of a punch press having a reciprocating punch head 2 driven from the eccentric 3 actuated from the driving pulley 4. The punch 5 is double as indicated at Fig. III, so that it intersects two portions of the felly material

at once. The die block 6 has double depressions corresponding to the double punch, as clearly seen in Fig. III.

A pipe 7 is secured to the punch frame 60 by cap screw 8 and extends parallel to the axis of the coil of felly material and serves as a support for the said coil 9, as seen in Fig. I. Secured to the punch press is an annular form 10 of the precise diameter 65 of the tire to be formed, the same being supported in position by a pair of screws 11, 11. The upper side of this form is open at 12, one end abutting the die member 6, as seen in Fig. III. The ends are supported 70 in proper relation by the cross bar 13, seen in Fig. II. Radially projecting guide pins 14 are on this ring to guide the end coil of the tire material to place.

Curved clamps 15, 15 are pivoted at 16, 75 16 to block 17 secured to the frame by screw 18 through the transverse slot 18' therein underneath the said ring shaped form 10. Levers 19, 19 pivoted at 20, 20 and connected at 21, 21 to the curved clamp pieces 80 15 serve to clamp the end coil very strongly against the annular form. These levers are actuated simultaneously by connecting rods 22, 22 extending downwardly to rock shaft arms 23, 23 carried on the rock shaft 24 85 disposed transversely between the coil of the material on the lower framework of the machine. This rock shaft is actuated by the latched lever 25 locking to the notched segments 26. When the end turn of the coil 90 is clamped securely to position the punch is thrown into gear, clips off a small part of the metal from the end of the coil exactly at right angles thereto, and also cuts off the end turn of the coil for the felly or rim. 95 The punch is detailed in Fig. III. As the succeeding turns of the coil are clamped in precisely the same way at each operation all the fellies or rims are precisely the same in size and when butt-welded or otherwise 100 secured together constitute perfect rims or fellies.

The machine is capable of use for fellies or tires of different cross section, but is especially well adapted to those of channel-shape, as here illustrated, because of the ease and facility with which the clamps can be fitted and adapted thereto, being of round rod as shown.

While I have shown a power punch for 110 use in this connection, it is clear that a hand operated punch might be made use of, al-

though of course the advantage of the power press would not obtain.

Having thus described my invention what I claim as new and desire to secure by Letters Patent is:

1. In a machine for cutting fellies or rims to length from a coil the combination of a punch press with suitable punching dies, a suitable support for the coil, an annular form at the end thereof secured to the said punch press and open at one side with recess for the die portion of the said punch, a die portion with double seats side by side for the opposite ends of the felly or rim, 10 one of which is close to the end of the coil, oppositely disposed curved clamps for embracing the opposite sides of the said coil to be cut off and forcing the same into contact with the said annular form, a locking 15 lever for controlling the same, and a reciprocating punch disposed to clip the metal at both points in the die seats, as described.
2. In a machine for cutting fellies or rims to length from a coil the combination of a 20 punch press with suitable punching dies, a suitable support for the coil, an annular form at the end thereof secured to the said punch press and open at one side with recess for the die portion of the said punch, a die portion with double seats side by side 25 for the opposite ends of the felly or rim, one of which is close to the end of the coil, oppositely disposed curved clamps for embracing the opposite sides of the said coil 30 to be cut off and forcing the same into contact with the said annular form, and a locking lever for controlling the same, as described.

3. In a machine for cutting fellies or rims to length from a coil the combination of a 40 punch press with suitable punching dies, a suitable support for the coil, an annular form at the end thereof secured to the said punch press and open at one side with recess for the die portion of the said punch, a die 45 portion with double seats side by side for the opposite ends of the felly or rim, one of which is close to the end of the coil, oppositely disposed curved clamps for embracing the opposite sides of the said coil to 50 be cut off and forcing the same into contact with the said annular form, as described.

4. In a device for cutting fellies or rims to length from a coil, an annular form, a clamp means for clamping the coil to the 55 said annular form, a die with double seat for receiving both ends of the coil to be cut off, a punch conformed to said seat and adapted to sever both ends of the felly or rim at the same operation, and suitable supports for the said punch and die, as specified.

5. In a device for cutting fellies or rims to length from a coil, an annular form, a clamp means for clamping the coil to the 60 said annular form, a die with double seat for receiving both ends of the coil to be cut off, a punch conformed to said seat and adapted to sever both ends of the felly or rim at the same operation, and suitable 65 power means for actuating the punch, as specified.

In witness whereof, I have hereunto set my hand and seal.

WILLARD E. RUPE. [L.S.]
